COAT HANGER

Henry M. Paulsen, Seattle, Wash.

Application December 17, 1947, Serial No. 792,132

2 Claims. (Cl. 223—89)

1

This invention relates to coat hangers, and particularly to adjustable forms therefor which are automatically locked in predetermined positions when a coat is supported thereby.

In the construction and use of coat hangers it is important that they be constructed economically with few parts and adapted to be adjusted for use for different size coats. It is especially important also that the assembled parts be automatically locked in such positions when used.

It is therefore an object of this invention to provide a coat hanger to meet such requirements with a minimum number of parts or wires cooperating together for telescopic adjustment. A particular object being to provide a wire coat hanger which may be easily adjusted into various lateral widths for various coats and which will be automatically locked in such desired positions by the weight of a coat suspended thereover or thereupon.

With these and other objects to be herein-after stated I have illustratively exemplified my invention by the accompanying drawings of which:

Figure 1 is a front elevation or vertical view of the assembled coat hanger in locked position. Figure 2 is a cross section view taken on line 2—2 of Fig. 1 with dotted lines to indicate the position of the supporting hook when the wires are freed for easy shifting or changing the dimensions thereof.

Like numerals on the different figures represent like parts.

This improved hanger is preferably formed of or from four pieces or sections of resilient wire movably connected together for use. Two relatively short shoulder sections 13 and 14 are twisted together at their upper ends beginning at the point 12 to provide a stiff supporting neck 11 which terminates with one member bent into a hook 10 for supporting the hanger. The lower extremities of these two wires or shoulder members are twisted forwardly for eyes at obtuse angles therewith as 15 and 16 forming eyes for slidable disposition over the upper portions of relatively longer cross body wire braces 23 and 24.

These cross braces overlap each other and carry eyes 25 and 26 which respectively embrace the other complementary brace for free slidable or telescopic movement for changing the width of the hanger. At suitable points these braces are bent upward into substantially U shapes for elbows 17 and 18, which in use fit beneath the outer edges of the shoulders of a coat and main-

tain the same in expanded position to prevent wrinkles being formed therein when suspended upon the hanger. The upper ends of the extended U bends carry eyes thereon 21 and 22 which are twisted backwardly downwardly and forwardly over the shoulder wire 13 and 14 in slidable relation therewith to facilitate the shifting in width of the elbows 17 and 18 and the lower braces 23 and 24. These eyes 21 and 22 and the other eyes 15 and 16 slope at obtuse angles with their respective bodies from which they are formed and thus create frictional contact with the enclosed wires as they are extended thereover forwardly from the lower members and backwardly from the upper shoulder members.

In order to provide for additional friction of the eyes last described and for locking the same into predetermined positions desired for the elbows, the lower portions of the shoulder sections indicated at 13' and 14' respectively are partially twisted and bowed forward over the adjacent portions 19 and 20 respectively of the upper sections of the U members; and the upper portions of the adjacent U members indicated as 19 and 20 are slightly twisted and bowed backward over such sections 13' and 14' thus forming sufficient friction when the hook is vertically disposed and such adjacent contacts at their greatest frictional disposition to effectively lock the shoulder wires and the lower brace wires in the predetermined positions for expansion desired. When the hook is bent backward as indicated by the dotted lines in Figure 2 then the positions of the twisted and bowed sections as 13' and 14' 19 and 20 will be thereby sufficiently released from friction to permit the operator to readily extend the elbows by sliding movements of the bowed portions within the respective binding eyes 15, 16, 21 and 22. When not in use the hook normally assumes a position shown in dotted lines which facilitates the shifting of the positions for the various garments. Then when a coat is draped over the hanger and the hook looped over any usual support the weight of the coat on the wires below causes the hook to straighten up vertically and brings the greatest strain on the frictional parts and automatically locks the elbows from accidentally changing from the desired positions.

Having described my invention I claim as new for Letters Patent:

1. In a device for supporting coats and garments, comprising, an upper and a lower pair of sections of resilient wires having top ends and lower bodies, wherein said upper pair thereof

is twisted together at the top ends thereof to provide a neck and supporting hook, and the lower bodies thereof being sloped outward and downward to provide shoulder members, the lower ends thereof being bent backward and into eyes, said lower pair of such sections having inner and outer portions said inner portions thereof disposed horizontally parallel for adjustments, the inner ends of such parallel lower portions provided with eyes encircling the adjacent lower portion for telescopic lateral movements for adjustments of width or sizes and said outer ends of such lower portions being turned upward and inward to provide elbows for expanding a garment thereover, the upper ends of such upturned elbows being threaded through the respective adjacent eyes on the lower ends of such upper shoulder members and there bent forward into eyes enclosing the shanks of such shoulder members to provide slidable relations between such upper and lower sections for adjustments of the elbows, and the portions of such upper shoulder sections and the upper portions of such elbow sections between the last described pairs of eyes being partially twisted and bowed over and toward the opposite adjacent respective sections for providing friction for locking the pairs of sections against lateral movement when the hook is vertically disposed by the weight of garment supported over the said sections.

2. A device for expanding and supporting coats and garments, comprising, an upper and lower pair of resilient wires, the upper pair thereof

having a supporting hook disposed approximately vertical normally above the same for supporting the device and garments, and having down sloping shoulders below the hook provided with eyes twisted on the lower extremities for guides and, said lower members having the major portions thereof disposed horizontally in parallel relation and their inner ends provided with eyes thereat for telescopic disposition with the adjacent member for lateral adjustments, elbows curved in the outward portions of such horizontal members oppositely disposed for stretching the garments thereover laterally and for supporting the same, and the top portions of such elbows being extended upward and telescopically connected with the lower portions of such upper pair of wires, the adjacent portions of such elbows and the upper pair of wires being twisted and bowed over and toward each other for creating friction between the same for locking the upper and lower pairs together to prevent accidental shifting positions thereof when the hook is vertical.
